US0D1112739S

(12) **United States Design Patent** (10) Patent No.: **US D1,112,739 S**
(45) Date of Patent: ** Feb. 10, 2026

(54) **SURGICAL TOOL CUTTING BIT**

(71) Applicant: **Joint Preservation Innovations, LLC**,
Naperville, IL (US)

(72) Inventors: **Sanjeev Bhatia**, Naperville, IL (US);
Peter J. Millett, Edwards, CO (US);
James Orrico, Evanston, IL (US)

(73) Assignee: **Joint Preservation Innovations, LLC**,
Naperville, IL (US)

(**) Term: **15 Years**

(21) Appl. No.: **30/026,609**

(22) Filed: **Oct. 3, 2025**

(57) **CLAIM**

The ornamental design for a surgical tool cutting bit as shown and described.

DESCRIPTION

FIG. 1 is a perspective view of a surgical tool cutting bit showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines depict portions of the surgical tool cutting bit that form no part of the claimed design.

1 Claim, 6 Drawing Sheets
